United States Patent Office

Des. 175,487
Patented Aug. 30, 1955

175,487

LOCK NUT

Stephen A. Young, Delphi, Ind.

Application October 7, 1954, Serial No. 32,575

Term of patent 14 years

(Cl. D54—2)

Fig. 1

Fig. 2

Fig. 3

Figure 1 is a plan view of a lock nut, embodying my new design.

Figure 2 is a side elevation of the same.

Figure 3 is a perspective view of the same.

I claim:

The ornamental design for a lock nut, substantially as shown.
